US0D1046570S

(12) **United States Design Patent** (10) **Patent No.:** **US D1,046,570 S**
(45) **Date of Patent:** **** Oct. 15, 2024**

(54) **JUICE EXTRACTOR**

(71) Applicant: **NUC ELECTRONICS CO., LTD.**,
Daegu (KR)

(72) Inventor: **Jong Boo Kim**, Daegu (KR)

(**) Term: **15 Years**

(21) Appl. No.: **35/519,744**

(22) Filed: **Jan. 19, 2023**

(80) **Hague Agreement Data**

Int. Filing Date: **Jan. 19, 2023**

Int. Reg. No.: **DM/227125**

Int. Reg. Date: **Jan. 19, 2023**

Int. Reg. Pub. Date: **Jan. 19, 2024**
